[57] CLAIM

The ornamental design for a spotting telescope, as shown and described.

DESCRIPTION

FIG. 1 is a perspective view of a spotting telescope showing my new design;

FIG. 2 is a side elevational view thereof, the opposite side being identical thereto;

FIG. 3 is a top plan view thereof;

FIG. 4 is a bottom plan view thereof;

FIG. 5 is an end view of the eyepiece end; and

FIG. 6 is a front elevational view of the objective lens end.

The broken line showing of the eyepiece housing is for illustrative purposes only and forms no part of the claimed design.
